United States Patent Office

Des. 194,143
Patented Nov. 27, 1962

194,143

PRAYER SHAWL

Norman Wolozin, 86-65 Bay Parkway, Brooklyn, and Herbert Wolozin, 1700A Harrison Ave., Bronx, N.Y.

Filed Sept. 5, 1961, Ser. No. 66,605

Term of patent 3½ years

(Cl. D3—16)

FIG. 2

FIG. 1 is a top plan view of a prayer shawl showing our new design; and

FIG. 2 is an enlarged fragmentary view thereof.

The essential features of our design reside in the full line disclosure on the drawing.

We claim:

The ornamental design for a prayer shawl, as shown.

References Cited in the file of this patent

Meyer Wolozin, 36 Eldridge St., New York, N.Y., copy-right July 1938, 7th page of religious furnishings shown center decoration on top center item.

John P. Daleiden Co. catalog No. 175, 1530-32 Sedgwick Street, Chicago 10, Ill., page 83, item No. 589-S, benediction stole.

Life magazine, May 28, 1951, page 105, scarf shown on rabbi.